UNITED STATES PATENT OFFICE

108,425

DESIGN FOR A MAUSOLEUM

Selma O. Colbe, Chicago, Ill.

Application November 6, 1937, Serial No. 72,662

Term of patent 14 years

To all whom it may concern:

Be it known that I, Selma O. Colbe, a citizen of the United States, residing at 4031 North Menard Avenue, Chicago, Illinois, have invented a new, original, and ornamental Design for a Mausoleum, of which the following is a specification, reference being had to the accompanying drawings, forming part thereof.

Fig. 1 is a front elevation of a mausoleum embodying my new design;

Fig. 2 is a side elevation of same;

Fig. 3 is a rear elevation of same;

Fig. 4 is a sectional plan view of same;

Fig. 5 is an enlarged detail view of the surface

ornamentation around the top of the mausoleum in the frieze indicated by A;

Fig. 6 is an enlarged detail view of the surface ornamentation on the urns in the circular panel indicated by B;

Fig. 7 is an enlarged face view of one of the door columns shown in Fig. 1, and

Fig. 8 is an enlarged fragmentary cross-section of the door columns shown in Fig. 4.

I claim:

The ornamental design for a mausoleum as shown.

SELMA O. COLBE.
